UNITED STATES PATENT OFFICE.

THOMAS W. BEHAN, OF BINGHAMTON, NEW YORK.

CLOTHES WRINGER.

Application filed December 29, 1920, Serial No. 433,773. Renewed October 30, 1922. Serial No. 597,920.

To all whom it may concern:

Be it known that I, THOMAS W. BEHAN, a citizen of the United States, and a resident of Binghamton, in the county of Broome 5 and State of New York, have invented certain new and useful Improvements in Clothes Wringers, of which the following is a description.

My invention relates to clothes wringers 10 and particularly to safety devices by means of which the pressure between the wringer rolls may be released in case of an emergency, as, for example, when an operator's finger gets caught between the rolls.

15 The object of my invention is to provide a safety device of this character which shall be reliable and instantaneous, and which can be operated with a minimum of effort.

Referring to the drawings, Figure 1 is 20 an elevation, partly in section, of a wringer embodying my invention; Fig. 2 is an enlarged fragmentary sectional view of my invention; and Fig. 3 is a sectional view taken on the line III—III of Fig. 2.

25 The wringer to which my invention is applied, as shown herein includes the usual rolls 1, 2, which may be geared together and driven manually or from any suitable source of power. The bearings for one of these rolls, in this case the upper one, are slidable 30 vertically and are pressed toward the other roll by compression springs, one of which is shown at 3. The opposite ends of these springs press against the ends 4 of the levers 35 which are pivoted to the frame at 6. The ends 7 of these levers are supported by the nut 8 upon the bolt 9. This bolt 9 is normally supported by the sleeve 10 and is provided at the top with a hand wheel or similar 40 device 11, so that it may be rotated to raise or lower the nut 8 and thus regulate the pressure between the wringer rolls 1 and 2.

The sleeve 10 is slidably mounted in the 45 frame of the wringer and is normally held in its elevated position by a releasable device. When this device is released the sleeve 10, carrying with it the bolt 9 and nut 8, is allowed to descend, and as a result the levers 5 are free to turn about their pivots 6 to release the pressure between the wringer rolls.

All of the above mechanism is old and is 50 here described only to illustrate one form of releasable wringer to which the particular form of releasing device which constitutes 55 my invention, may be applied.

As shown in the drawings, the sleeve 10 is provided with a notch 12. The retaining or tripping device heretofore used in connection with the wringer above described has been in the form of a single integral bell 60 crank lever pivoted to the frame of the wringer, one end of the lever fitting in the notch 12 and the other end being arranged to be struck by the hand to remove the first mentioned end from the notch for releasing 65 the sleeve. It has been found in practice, however, that an extremely heavy downward pressure is exerted by the sleeve upon the tripping lever, especially at times when it becomes necessary to operate the trip due to 70 the operator's fingers, or an excessively thick piece of material, becoming wedged between the rolls. As a result it often requires more force than the ordinary operator can exert to operate the form of trip above described. 75 That, of course, seriously detracts from its usefulness as a safety device. Furthermore, it has been found that there is a considerable wear of the material between the notch 12 and the contiguous end of the tripping 80 lever.

To obviate these and other objections to the integral tripping lever, I have provided, in lieu thereof, the toggle form of tripping device which I shall now describe.

This device includes the lever 13, which is pivoted at 14 to the frame of the wringer and which may be bifurcated at the top, if desired. Pivoted to this lever at 15, near its upper end, is the lug 16 adapted to rest in 85 the notch 12 as indicated in the drawing.

To remove the lug 16 from the notch 12, I employ the bell crank lever 17 which is also pivoted to the frame at 14, and the short end 18 of which contacts with the lower extension 19 of the pivoted lug 12. This lever 17 is normally held in the position shown in the drawing by the spring 20.

As appears clearly from the drawing, the lug 16 and the lever 13 form together what is 100 in effect a toggle, normally unbroken. Owing to the positioning of these members this toggle will resist any amount of vertical pressure from the sleeve 10 without breaking. This is due to the fact that when the 105 toggle is in its supporting position its hinge or elbow 15 is very slightly to the right (as viewed in Fig. 1) of the line of pressure exerted by the sleeve 10 upon the toggle. Accordingly the normal effect of this pressure 110

is to force the lug 16 more tightly against the sleeve and not to break the toggle. However, when it is desired to release the sleeve 10, it requires but slight pressure upon the lever 17 to cause the end 18 contacting with the lug 16 to move the lug so that the elbow 15 is moved to the left of the line of pressure and the toggle is broken, with the result that the sleeve is immediately and completely released, the lever 13 moving about its pivot in a counter clockwise direction and the lug 16 moving about its pivot in a clockwise direction. I preferably provide a stop, such as indicated at 21, to limit the movement of the lug 16 about its pivot.

To reset the sleeve 10, it is necessary merely to unscrew the bolt 9 slightly by means of the hand wheel 11 and then raise it sufficiently so that the spring 17^a, interposed between the frame and the lower end of lever 13, may restore the toggle to its supporting position. Thereafter the pressure between the rolls may be regulated as desired by manipulation of the hand wheel 11.

The terms and expressions which I have employed are used as terms of description and not of limitation, and I have no intention, in the use of such terms and expressions, of excluding any equivalent of the features shown and described, or portions thereof, but recognize that various modifications are possible within the scope of the invention claimed.

What I claim is:

- 35 1. In a wringer or the like provided with a pair of parallel rolls and releasably supported means for exerting pressure between said rolls, the combination of a supporting device for said means, said device including a toggle which is unbroken when in supporting position, and manually operable means independent of said toggle for breaking said toggle to release said first mentioned means.
- 40 2. In a wringer or the like provided with a pair of parallel rolls and releasably supported means for exerting pressure between said rolls, the combination of a supporting device for said means, said device including a toggle which is unbroken when in supporting position and which is so arranged that the application of pressure through said means does not tend to break it, and manually operable means independent of said

toggle for breaking said toggle to release said first mentioned means.

3. In a wringer or the like provided with a pair of parallel rolls and releasably supported means for exerting pressure between said rolls, the combination of a supporting device for said means, said device including a lever pivoted to the wringer frame, a lug pivoted to said lever and in supporting contact with said means, said lug and lever constituting a toggle, and a manually operable means for breaking said toggle to release said first mentioned means.

4. In a wringer or the like provided with a pair of parallel rolls and releasably supported means for exerting pressure between said rolls, the combination of a supporting device for said means, said device including a lever pivoted to the wringer frame, a lug pivoted to said lever and in supporting contact with said means, said lug and lever constituting a toggle, and a manually operable lever also pivoted to the wringer frame for breaking said toggle, to release said first mentioned means.

5. In a wringer or the like provided with a pair of parallel rolls and releasably supported means for exerting pressure between said rolls, the combination of a supporting device for said means, said device including a lever pivoted to the wringer frame, a lug pivoted to said lever and in supporting contact with said means, said lug and lever constituting a toggle, and manually operable means adapted to contact with said lug and move it angularly with relation to said lever to break said toggle and thereby release said first mentioned means.

6. In a wringer or the like provided with a pair of parallel rolls and releasably supported means for exerting pressure between said rolls, the combination of a supporting device for said means, said device including a lever pivoted to the wringer frame, a lug pivoted to said lever and in supporting contact with said means, said lug and lever constituting a toggle, manually operable means adapted to contact with said lug and move it angularly with relation to said lever to break said toggle and thereby release said first mentioned means, and spring means for restoring said lever and lug to supporting position.

THOMAS W. BEHAN.
